HANGER FOR TROUSERS

William A. Nelson, Minneapolis, Minn., assignor
of one-fourth to Leon R. Sanborn, Minneapolis,
Minn.

Application April 25, 1940, Serial No. 331,553

6 Claims. (Cl. 223—83)

My invention relates to garment hangers and particularly to hangers for trousers.

Many types of trouser hangers have been devised, but some of such hangers cause undesired fold marks in the trousers hung on them and other types are so constructed that the trousers may easily be disengaged from the hanger.

An object of my invention is to provide a trousers hanger so arranged as to support a pair of trousers by the cuffs thereof in such manner as to reliably support the trousers and not produce undesired fold marks or wrinkles in the same.

Another object is to provide such a trousers hanger which is readily adjustable for use with trouser cuffs of various dimensions.

Still another object is to provide such a hanger including means for retaining the same in any adjusted condition thereof.

Still another object is to provide such a trousers hanger which may be readily made in combination with a coat hanger structure.

A further object is to provide such a trousers hanger of simple, light, compact, rugged and inexpensive construction.

These and other objects and advantages of the invention will more fully appear from the following description made in connection with the accompanying drawing, wherein like reference characters refer to the same parts throughout the views, and, in which,

Fig. 1 is a front view of an embodiment of my invention with the cuffs of a pair of trousers operatively associated therewith;

Fig. 2 is an end view of the device shown in Fig. 1;

Fig. 3 is a front view of a portion of the device of Fig. 1 drawn to enlarged scale;

Fig. 4 is a top view of the structure shown in Fig. 3;

Fig. 5 is a sectional view taken on the line 5—5 of Fig. 3, as indicated by the arrows;

Fig. 6 is a front view of a slightly modified form of the structure shown in Fig. 3; and

Fig. 7 is a front view of a slightly different embodiment of my invention.

Referring to the drawing and particularly to Figs. 1 to 5 inclusive an embodiment of my invention is shown which is constructed for cooperation with a wire coat hanger 8 which is of generally conventional form but is modified in portions in accordance with my invention.

For association with the coat hanger 8 I provide a pair of structures each affording elements or prongs adapted and intended for insertion in the interiors of the cuffs of a pair of trousers,

such as the trousers T, a portion of which is shown in Figs. 1 and 2. For this purpose I prefer to use a slender elongated member 9 formed of bendable but relatively stiff material. The member 9 may be made of suitable metal wire. The wire 9 is bent as illustrated in Fig. 3 to provide a series of spaced parallel portions joined by curved portions of the wire 9. The parallel portions of the wire 9 formed in the medial part of the wire 9 constitute upwardly extending elements or prongs 9a for insertion in interiors of the cuffs of a pair of trousers. The endmost ones 9b of the parallel portions of the wire 9 extend upwardly to terminate at a level in the vicinity of the levels of the upper ends of the prongs 9a. The upper end portions 9c of the endmost parallel portions 9b of the wire 9 are bent, as best shown in Fig. 5, to form hooks which may be hooked on the horizontal bar 8a which constitutes the lowermost portion of a coat hanger, such as the hanger 8. As best seen in Figs. 3, 4, and 5, respective ones of the prongs 9a are disposed at opposite sides of the bar 8a.

Means is provided on the bar 8a for holding the respective cuff supporting members 9 at various adjusted distances apart and yet enabling adjustable movement of the cuff supporting members 9 longitudinally of the bar 8a. For this purpose the bar 8a in each end portion thereof is provided on a horizontally facing side thereof with a longitudinal extending series of spaced projections 8b. These projections 8b may be formed in any suitable manner, but I prefer to form them by suitably pinching the material of the bar 8a to press portions of the material outwardly in such manner as to form the projections 8b. The hooks 9c of the cuff engaging members 9 are normally disposed on the bar 8a at points thereon between the projections 8b so that the projections 8b will restrain the hooks 9c from movement longitudinally of the bar 8a. However, the device is so constructed as to enable adjustment of the positions of the cuff engaging members 9 in a direction longitudinally of the bar 8a. As will be seen in Fig. 5, the portions of the hooks 9c engaging the top and sides of the bar 8a are proportioned to relatively snugly adjoin the periphery of the bar 8a, but the portions of the hooks 9c normally disposed below the bar 8a are bent in such direction as to leave a space 9d between the bottom portions of the hook 9c and the bottom of the bar 8a of dimensions slightly greater than the dimensions of the projections 8b. When it is desired to adjustively move one of the members 9 along the bar 8a,

the member 9 is swung upwardly and to the right through an angle of ninety degrees, as viewed in Fig. 5, to align the spaces 9d with the projections 8b. It should be apparent that the members 9 when in such position may be moved longitudinally of the bar 8a without interference from the projections 8b. When the member 9 has been moved the desired distance it may be released to again assume its depending normal position, as shown in Fig. 5, the hooks 9c being, of course, positioned at points on the bar 8a between ones of the projections 8b.

Fig. 6 illustrates a form of my device which is identical with the form described above except that the bent wire member 10 thereof is so constructed that the endmost parallel portions 10a thereof extend upwardly to a point a moderate distance above the tops of the cuff engaging prongs 10b of the member 10. The upper ends of the portion 10a are formed into hooks 10c identical with the hooks 9c of the device of Figs. 1 to 5. The cuff engaging member 10 is associated with a bar such as the bar 8a of the hanger 8 having projections 8b thereon as described above. The portions of the wires 9 and 10 of which the hooks 9c and 10c are formed may be so bent that the end of the wire is in closely adjoining relation with a portion of the endmost parallel parts of the wires 9 and 10 so as to form the hooks 9c and 10c into substantially closed loops.

Fig. 7 illustrates a somewhat different form of the device in which a flat structure 11 having the general shape of a coat hanger is formed of suitable sheet material such as heavy cardboard, for example. A metal hook 12 by means of which the hanger may be hung upon a support is attached to the upper middle portion of the flat member 11 by suitable means such as the rivet 13. A flat bar 14 which may be made of any suitable sheet material is laid against one side of the lower marginal portion of the member 11 in closely adjoining parallel relation therewith. If desired the flat bar 14 may be duplicated by placing a similar bar on the remaining side of the flat member 11. The bar or bars 14 are secured to the flat member 11 at spaced points by suitable means such as for example stitching 15. Cuff supporting members 16 which may be identical with the previously described cuff supporting members 9 may be hooked onto the flat bar 14 at respective points thereon near the respective ends thereof. If duplicate bars 14 are provided on opposite sides of the member 11 it is preferable that openings 11a through the flat member 11 be provided immediately above the respective end portions of the bars 14 and that the cuff supporting member 16 be hooked onto the combined structure afforded by the pair of bars 14.

In the device of Fig. 7 means may be provided tending to prevent movement of the cuff supporting member 16 longitudinally of the bars 14 and yet enabling adjustive movement of the cuff supporting member 16 along the bar 14. For this purpose respective end portions of the bar 14 are provided with a series of notches 14a in which the upper portions of the hooks 16a of the cuff supporting member 16 may normally be disposed.

The method of attaching a pair of trousers to any of the above described forms of my trouser hanger consists of placing one of the cuffs 17 of the trousers T on one side of the cuff supporting members 9, 10 or 16, and the other cuff 17c on

the other side of the cuff supporting members. One cuff is placed on prongs of the respective cuff supporting members in such manner that these prongs will project up into the interior of the cuff at opposite ends thereof so as to engage the creased end portions of the cuff 17. The other cuff disposed at the opposite side of the cuff supporting members is similarly placed on prongs of the respective cuff supporting members. As viewed in Fig. 1, one of the trouser cuffs 17 will be placed on the right-hand prongs 9a of the respective cuff supporting members 9 and the other cuff will be placed upon the left-hand prongs 9a of the respective cuff supporting members 9. Thus the spacing between the prongs on which one cuff is supported will be the same as the spacing between the prongs on which the other cuff is supported. As previously described the cuff supporting members are adjustable in position longitudinally of the bar on which they are hooked. It should be apparent that the spacing between the respective cuff supporting members should be adjusted so that the cuffs attached thereto will be placed under slight tension when placed on the hanger in the above described manner. Also it should be apparent that a pair of trousers attached to my hanger in the manner described will hang in an inverted position.

It should be apparent that while I have shown the cuff supporting members 9, 10 and 16 in association with coat hanger structures, they could also be quite readily hooked onto any suitable horizontal bar which may not be part of a coat hanger. Furthermore, such a bar could readily be provided with projections such as the projections 8b of Figs. 3, 4, and 5 or could be provided with notches such as the notches 14a of Fig. 7.

It will, of course, be understood that various changes may be made in the form, details, arrangement and proportions of the various parts without departing from the scope of my invention.

What is claimed is:

- 45 1. A garment hanger comprising, structure arranged for removable connection thereof to a support and including an elongated horizontal bar, and a pair of trouser cuff-engaging members associated with longitudinally spaced portions of said bar and each comprising, an elongated slender member formed of bendable but relatively rigid material, said member being bent in its medial portion to form a series of spaced, parallel, upwardly projecting trouser cuff-engaging elements and, in its end portions, being bent upwardly parallel to said elements to have ends disposed at at least as high a level as the upper portions of said elements, said ends of said member being formed into hooks connectible with said bar for support of said member therefrom, and said bar having, on one of its horizontally facing sides, a longitudinally extending series of small, spaced, outwardly projecting elements between ones of which said hooks may be disposed whereby said last-mentioned elements will normally restrain said hooks from movement longitudinally of said bar, said hooks being so formed that the top and sides thereof closely hug said bar between said last-mentioned elements and the bottom portion affords a space between the same and said bar at least as large as said last-mentioned elements whereby said member, when swung upwardly to align said space with said last-mentioned elements, is free for being adjustively moved along said bar.
- 50
- 55
- 60
- 65
- 70
- 75

2. In a garment hanger, a body having means for engaging a support, said body including a normally horizontal bar having projections extending therefrom short distances laterally thereof and having a relatively smooth upper surface, and a pair of garment engaging units secured to said bar, said units including looped members surrounding said bar, and said looped members being elongated downwardly when said units are hanging from said bar in a vertical position, and said units when in a horizontal position being slidably along said bar, said elongated loops being adapted to pass over the projections on said bar.

3. The structure in claim 2 and said projections having substantially rounded edges and being spaced apart only a sufficient distance to permit said loops to lie between them when said garment engaging members are vertically suspended from said bar.

4. In a garment hanger, a relatively thin sheet of material normally disposed in a vertical plane and having the general shape of a coat hanger, means connected to said sheet for securing the same to a support, and a reenforcing bar extending along the lower portion of said sheet substantially from end to end thereof and secured to said sheet substantially throughout its length, and said sheet having spaced cut-away portions adjacent said bar inwardly from the ends thereof and garment engaging members having portions extending through said cut-away portions and removably positioned on said reenforcing bar at said cut-away portions.

5. A garment hanger comprising a sheet of relatively thin material normally disposed in a vertical plane and having the general shape of a coat hanger, support engaging means at the upper portion of said sheet, a sheet re-enforcing bar extending along the lower portion of said sheet, said sheet and bar being connected at their ends and at an intermediate point between said ends, said sheet and bar being spaced from each other at points between their end and intermediate connections, said bar having a plurality of projections formed on those portions thereof spaced from said sheet, and garment engaging elements detachably mounted upon and adjustably movable on those portions of said bar spaced from said sheet.

6. In a garment hanger, a body having means for engaging a support, said body including a normally horizontal bar of relatively small cross section and having projections thereon at relatively closely spaced points, a pair of garment engaging units comprising wires bent to provide at least two vertically extending garment engaging tongues and each unit having hanger bar engaging portions lying at opposite ends of the unit, said bar engaging portions having hooks lying around said bar and adjustably movable to different points along said bar and engageable by said projections, said garment engaging tongues of each of said units being staggered and offset from the longitudinal axis of said bar.

WILLIAM A. NELSON.
